UNITED STATES PATENT OFFICE.

WILLIAM G. FLANDERS, OF LANSINGBURG, NEW YORK.

STEAM-COOKER.

SPECIFICATION forming part of Letters Patent No. 225,584, dated March 16, 1880.

Application filed February 25, 1879.

To all whom it may concern:

Be it known that I, WILLIAM G. FLANDERS, of Lansingburg, in the county of Rensselaer and State of New York, have invented certain 5 new and useful Improvements in Domestic Steam-Cookers, of which the following is a specification.

The objects of my invention are to render the closing of the cover and extension steam- 10 tight, so as to prevent the escape of odors from the food being cooked—such as onions, cabbage, salt codfish, and the like—entering the room through the escape of steam, as in steam-cooking kettles heretofore in use; and it consists in the construction, combination, and arrangement of the several parts, as hereinafter more fully described and set forth.

Figure 1 is a view of my steam-cooker connected together. Fig. 2 is a vertical section 20 of a portion of the same without the extension. Fig. 3 is a detached view of a wire-net diaphragm.

A represents the lower section or boiler portion of the cooker, which is made with its bottom somewhat larger than the boiler-hole over which it is to be placed. B is the lower steam-chamber, provided with an open wire-net diaphragm or support, C, (shown removed therefrom in Fig. 3,) and upon which meats, vegetables, or other food may be placed to be 30 cooked by steam arising from water placed in the boiler A, which is supplied with a water-supply tube, D, placed upon the outside of the steam-chamber B, and extending downward to the boiler portion A, where it enters the side of the same, and thence downward upon the inside to within about one-half of an inch of the bottom, where it terminates.

To the top of the supply-tube D is affixed a 40 cap, e, which may be removed to renew the water in the boiler, and when it is evaporated or nearly boiled away, leaving the lower end of the supply-tube D open or above the water, the steam enters the same and ascends to the whistle t, provided in the cap e, where it escapes, thereby indicating to the cook or attendant that more water is required in the boiler.

To the side of the steam-chamber B is also 50 attached a steam-escape pipe, E, which enters

the side of the boiler A and passes downward through its bottom near the center, so as to have an outlet within the boiler-hole of a stove when placed thereon.

To the upper end of tube or steam-escape pipe E is fitted a socket, g, which receives the end of a steam-escape pipe, E', which is secured to the outside of the steam-chamber B², which is provided at its lower edge or bottom portion with a downward-projecting flange, F, 60 which is beveled inwardly and has a packing-band of rubber or other flexible material, H, surrounding said flange and secured in any suitable manner, so that when the flange thus packed is inserted within the mouth of the lower portion, as shown in Fig. 2, and pressed downward, it will form a steam-tight joint, and be held connected thereto by flat springs I, secured to the outside of the extension or steam chamber B², their lower ends being provided 70 with hooks turned inwardly, so as to engage with the projecting rim or catches, as shown at the left-hand side of Fig. 1, and at the opposite side the spring I' is shown disengaged from the catch by being forced outward near 75 its lower end by a short hinged lever, J, which, if pressed downward, forces the hook from the catch, and thus permits the removal of the upper portion whenever desired.

To the top of steam-chamber B², Fig. 1, is 80 shown a cover, K, provided with flat springs L, to the outer free ends of which is pivoted a loop, M, which is hooked over a catch, c, upon the steam-chambers B, which holds the said cover K steam-tight with the mouth of the 85 steam-chamber, as shown. This cover has a downward-projecting flange, N, which is beveled inwardly and surrounded by an elastic rubber or flexible packing-band, P, secured thereto in any suitable manner, and such cover 90 is made to fit steam tight upon either the upper or lower steam-chamber, as shown.

To the interior of the cover K is secured a spring-valve, R, which opens upward by the pressure of steam generated within the cooker, 95 which, when increased beyond the pressure that may be required in cooking, passes through said valve R and enters the short angle-pipe S, which fits into a socket at the top of the steam-escape pipe E, thus conveying all odors arising 100

ing from cooking cabbage, onions, or the like directly into the stove and fire, where they pass off without entering the room.

5 T represents three or more feet or legs projecting downwardly from the lower edge of the flange F of the extension or steam chamber B², as shown in Fig. 1.

Having thus described my invention, what I claim is—

In combination with steam-chamber B², having the flat hooked springs I, the hinged levers J, constructed and arranged to operate substantially as shown and described, as and for the purposes set forth.

WILLIAM GATES FLANDERS.
